TELEVISION SIGNAL CONTROL CIRCUIT

Robert E. Rutherford, Rutherford, and Richard L. Campbell, Maywood, N. J., assignors to Allen B. Du Mont Laboratories, Inc., Passaic, N. J., a corporation of Delaware

Application December 18, 1941, Serial No. 423,460

4 Claims. (Cl. 178—7.2)

This invention relates to a television transmission system in which clipping and limiting circuits are provided. Linear amplification of the video signals takes place and abrupt limitation of signal level is provided to prevent video components from getting above the blanking level into the synchronizing region. Means are also provided for controlling the pedestal level and for inserting direct current components in the television signal.

In carrying out this invention a blanking signal is applied to the amplified signal from the pick-up camera, the pedestals thus formed are clipped to form flat topped pedestals, the signal is amplified, and the pedestals are again clipped and amplified. A diode tube is used for clipping, and linear response below the clipping level can be maintained at all times with this invention. The clipping level can be readily and accurately adjusted by varying the direct current bias, the pedestal height is effectively controlled after clipping, and the invention will operate over a very wide range of signal levels.

In the conventional system of television transmission it has been customary to arrange the receivers with automatic background control for the average brilliance of the pictures, facilities being included for maintaining the cut-off voltage of the cathode-ray tube at a point corresponding to the black level of the composite synchronizing wave form. In order for the scenes to be received properly, it has been necessary for the transmitter to adjust the average illumination by means of suitable composition of the transmitted wave form. The average axis of the useable picture wave form determines the average brilliance on the receiving tube with respect to the black level. Consequently, it has heretofore been necessary to adjust the average level of the wave form at the transmitter with respect to the black level. This can be done by purposely shifting the black level to a new point so as to give a variation between the range of the black level and the average level of the useable picture signal. Heretofore it has been necessary to change this range, particularly for motion pictures where the total brightness of the scenes varies quickly from frame to frame.

By the present invention the pedestal adjustment is made much simpler. Furthermore, by providing this pedestal adjustment one can compensate for inadequate lighting on a dull day out of doors so as to provide a reasonably bright picture on the television receivers. Also, by reduction of the pedestal level one can compensate

for too much light and adjust the signals to give the best over-all performance through the amplitude limitations of the transmitting and receiving system. The camera sensitivity, the lens aperture, and the amplifier gain also need to be adjusted to further balance the average scenes being picked up and obtain the best results.

The invention will be understood from the description in connection with the accompanying drawings, in which:

Fig. 1 is a block diagram showing an arrangement of apparatus used in the invention;

Figs. 1a, 1b, 1c, 1d, 1e, 1f, and 1g are diagrams of signals at different stages;

Fig. 2 is a diagram having a signal associated therewith showing a diode for use in the invention;

Fig. 3 is a diagram showing a cathode-loaded stage driving a clipping diode;

Fig. 4 is a diagram showing a plate-loaded stage driving a clipping diode; and

Fig. 5 shows two diodes for cascaded clipping of signals in a synchronizing generator.

In the drawings, reference character 1 in Fig. 1 indicates an iconoscope or television pick-up device, and the words in the blocks 2, 3, 4, 5, 6, 7 and 8 of the diagram of Fig. 1 show the arrangement of different devices in accordance with this invention.

Reference character 11 (Fig. 1a) indicates a video signal of the well known sort, and 12 in Fig. 1b indicates a blanking signal for the video signal 11.

Reference character 13 in Fig. 1c indicates the video signal after the blanking signal 12 has been applied, the dotted line 14 indicating where the pedestals 15 are to be clipped to form the signal 16 as shown in Fig. 1d with the flat topped pedestals 17. Fig. 1e shows the signal 16 of Fig. 1d amplified to 16' with the pedestals amplified as indicated at 17', and the dotted line 18 shows where this pedestal is to be clipped. The clipping results in the formation of the signal as indicated in Fig. 1f by the reference characters 19 and 20, the characters 20 representing the pedestals further clipped. The signal is finally amplified as indicated in Fig. 1g into the signal 19' with the pedestals 20'.

In Fig. 2 is shown, in more detail, the unit designated by the block diagram 5 in Fig. 1 and called a pedestal clipper diode. The mixed signal is indicated at the top of this Fig. 2 by reference character 25, and consists of the desired picture component 26 and spurious signal 27

which is superposed upon the inserted blanking 28. The dotted line 29 represents the level at which clipping will occur in the diode 30, this level being determined by the setting of the bias voltage by the movable arm 31 on the potentiometer 32. This signal wave form 25 is fed into the plate 33 of the diode 30, which has a resistance 34 connected to ground. A load resistor 35 is in the circuit of the cathode 37 of the diode 30, and the condenser 38 couples the clipped output signal to the output lead wire 39 on which appears the clipped wave form 40 consisting of the desired picture components 26 and the square topped clipped pedestals 41. This diode 30 removes the extraneous wave form 27 and prepares the signal for passage to the remaining television equipment.

This diode clipper, which is used in the position of block diagram 5 (Fig. 1), not only removes the extraneous signals during the blanking interval, but, further, prevents any possibility of picture components extending up into the amplitude region which is to be devoted to synchronizing. It is very important that no signal wave forms reach into this region except the desired synchronizing impulses which are introduced later on to be mixed with the output wave forms of Fig. 1f or Fig. 1g to compose the well known composite television signal.

An additional clipper in the television amplifier chain may also be used whenever desired to limit the excursions in the white direction so as to prevent overload of the television transmitter.

By use of these clippers, it is possible to transmit motion picture film in which the contrast range, and consequently the level of the picture signal amplitude, changes from low values to very high values, since the clippers will prevent the pictures from exceeding the useful range and encroaching upon the synchronizing level or encroaching upon the whiter than white level. This restriction of amplitude is automatic and works far more rapidly than one could operate a manual gain control to restrict the output signal from the amplifier.

A modification of the invention is shown in Fig. 3, which includes a tube 50 that is connected as a cathode follower stage to serve as an impedance transformer. The signal, such as 25 above, is fed to the terminal 51 and passes through the condenser 52 to the grid 53 of the tube 50. The resistor 54 is inserted between this grid and ground to hold the grid at the proper average voltage. In some cases this resistor 54 may be returned to a positive potential. The plate 55 and screen grid 56 of the tube 50 are connected to a positive supply voltage. The load circuit of the tube 50 consists of the resistor 58 in the circuit of the cathode 59. Essentially the same signal appears on the lead 60 from this cathode as on the lead 51, except that this signal is driven by a much lower impedance which is capable of feeding the following diode 63 without distortion. The lead 60 from tube 50 is connected to the plate 64 of the diode 63, and the cathode 65 of this diode is connected through the load resistor 66 to a source of variable bias which may be the potentiometer 67 with its slider 68, one end of this potentiometer being connected to a source of positive potential and the other end being connected to ground. The output signal is coupled by condenser 69 to the remainder of the television equipment. By adjustment of the slider 68 the signal fed in at 51 can

be clipped to yield a square topped signal similar to that shown in the wave form 40 of Fig. 2.

A further modification of the invention is shown in Fig. 4 in which the clipping diode is fed from a plate-loaded vacuum tube 75. The signal to be applied to the terminal 76 would in general be the reverse polarity from the wave form shown by Fig. 2. It is fed through the condenser 77 to the grid 78 of the tube 75. The grid leak-resistor 79 is returned to a suitable bias supply represented as a battery 80. The cathode 81 is grounded in this embodiment but may utilize self-bias in the well known way. The screen grid 83 is connected to a positive supply, and the plate 84 has a load resistor 86 returned to a positive supply. The plate 84 is connected directly to the plate 88 of the diode 89 which is to clip off the unwanted components of the signal. The cathode 91 has a load-resistor 92 connected by a slider 93 to a potentiometer 94 which provides variable bias by means of one end connected to ground and the other end connected to a positive potential. The output signal is connected by the condenser 95 to the television equipment which follows.

Another modification of the invention is shown in Fig. 5 wherein cascaded clipping diodes are used for eliminating amplitude excursions on both sides of a desired wave form. In this figure, the wave form 100 is applied to the plate 102 of the diode 103. Such a wave form as this wave form 100 has been described in the Campbell Patent 2,249,942 in connection with the generation of a composite synchronizing signal consisting of short square impulses at horizontal line frequency combined with a burst of high frequency carrier at a repetition rate corresponding to vertical field frequency. In this patent is shown means for clipping off to eliminate the portions of signal above and below the desired signal region, but this method used the principle of overloading amplifier tubes, which involves the non-linearity referred to elsewhere.

This earlier procedure is simplified, as shown in Fig. 5, by using two simple diodes which in practice can even be in a single envelope. The resistor 104 is connected from the plate 102 to ground and maintains this plate at its proper average operating voltage. The cathode 105 of the diode 103 is returned through the load resistor 107 to a variable bias potentiometer 108 whose adjustment determines the extent of clipping in the negative direction. The signal on this cathode 105 is represented by the wave form 109 which shows that the negative unwanted portion 111 of the wave form 100 has been removed. The positive portion 112 still remains, and is clipped by diode 115 in which the cathode 116 is connected to the output signal from the cathode 105 of the first diode 103. The final output signal appears on plate 117, which is returned through resistor 118 to another source of variable bias voltage consisting of the potentiometer 119. The output signal as shown at 121 is conducted by means of lead 122 through condenser 123 to the remaining equipment.

It has been found that the first blanking clipping means described above can be pre-set to take care of all normal ranges of signals. A second adjustable clipping diode preferably located rather along in the amplified chain has proved most satisfactory for adjusting the pedestal level when changes of scene are encountered in television pictures. This pedestal adjustment is placed as far along in the amplifier chain as seems practical in order that low frequency surges in the output may be minimized.

It has been found that the use of diode clippers for providing the square topped blanking signal is a considerable improvement over the triode saturation type limiters, because the diode clipper fundamentally maintains signal linearity up to the point where clipping occurs. Also the adjustment of the clipping level is readily made simply by changing the direct current bias. It is also possible with the diode clippers to adjust easily the range of signal levels to be accepted, whereas in the old methods of saturated amplifying tubes the range of signal amplitude which can be passed is determined rather definitely by the characteristics of the triode or pentode tube which is used. Furthermore, the diode tube is extremely simple, and a single tube can be made to do the clipping action.

It is desirable in some cases to provide an automatic method of changing the average bias supplied to the clipping diode used in the block diagram 7 of Fig. 1 for use in adjusting the pedestal level. This automatic change of bias can be incorporated in connection with a photoelectric cell which integrates the average illumination of the successive frames of motion picture film, and in this way the combination of the photoelectric cell and the automatic adjustment of the bias on the pedestal controlling diode truly provides a direct current insertion at the transmitter which will follow the average brilliance of the motion picture scenes.

What is claimed is:

1. In a television signal control circuit, means for mixing video and blanking signals, means for establishing flat top pedestals for synchronization, and means comprising a diode tube for controlling and varying the amplitude of said pedestals.
2. In a television signal control circuit, means for mixing video and blanking signals, a single tube clipping means for establishing flat top pedestals for synchronization, and means comprising a diode tube for controlling and varying the amplitude of said pedestals.
3. In a television signal control circuit, means for mixing video and blanking signals, means for establishing flat top pedestals for synchronization, and means comprising an impedance transformer and a diode tube for controlling and varying the amplitude of said pedestals.
4. In a television signal control circuit, means for mixing video and blanking signals, clipping means for establishing flat top pedestals for synchronization, means comprising a diode tube for controlling and varying the amplitude of said pedestals, and means comprising cascaded clipping diodes to control the pedestal height after clipping.
